Patented Sept. 6, 1921.

Inventor:
Ruby Gilbert,
by Mrs. T. G. Gilbert
her Attorney.

UNITED STATES PATENT OFFICE.

RUBY GILBERT, OF ETIWANDA, CALIFORNIA.

DESIGN FOR ROMPERS.

58,902.

Specification for Design. Patented Sept. 6, 1921.

Application filed October 5, 1920. Serial No. 414,877. Term of patent 7 years.

To all whom it may concern:

Be it known that I, RUBY GILBERT, a citizen of the United States, residing at Etiwanda, in the county of San Bernardino, State of California, have invented a new, original, and ornamental Design for Rompers, of which the following is a specification, reference being had to the accompanying drawing, forming part thereof.

The figure is a perspective view of the rompers, showing my new design.

I claim:

The ornamental design for a romper, as shown.

RUBY GILBERT.

Witnesses:

VIRGINIA BERNINGER,
FLORENCE EHRGOTT.
